Primary Examiner — Amy C Wierenga*Assistant Examiner* — Chariton Alexakis(74) *Attorney, Agent, or Firm* — Hawaii Patent Services; Nathaniel K. Fedde; Kenton N. Fedde(57) **CLAIM**

The ornamental design for a hydrogen rich water cup as shown and described.

DESCRIPTION

FIG. 1 is a forward left pitch view of a hydrogen rich water cup, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view thereof with the lid closed. The broken lines depict portions of the hydrogen rich water cup that form no part of the claimed design.

1 Claim, 9 Drawing Sheets(56)
